DESIGN FOR A TOOTHBRUSH HOLDER

David Beilock, New York, N. Y.

Application May 1, 1945, Serial No. 119,336

Term of patent 14 years

(Cl. D4—3)

To all whom it may concern:

Be it known that I, David M. Beilock, a citizen of the United States, residing in the city, county, and State of New York, have invented a new and original Design for Toothbrush Holder, of which the following is a specification, reference being had to the accompanying drawing, forming part thereof:

I claim:

The ornamental design for a toothbrush holder, as shown.

DAVID BEILOCK.
